BOWL

Harry S. Konokawa, New York, N. Y.

Application June 11, 1949, Serial No. 3,207

Term of patent 7 years

(Cl. D44—10)

To all whom it may concern:

Be it known that I, Harry S. Konokawa, a citizen of Japan and a resident of the city of New York, in the county of New York and State of New York, have invented a new, original, and ornamental Design for Bowl, of which the following is a specification, reference being had to the accompanying drawing, forming part thereof.

Fig. 1 is a top plan view of a bowl, showing my new design.

Fig. 2 is a side view thereof, and

Fig. 3 is a sectional view taken on the line 3—3 of Fig. 1.

I claim:

The ornamental design for a bowl, substantially as shown.

HARRY S. KONOKAWA.
